HANDLE ASSEMBLY

Deo R. Mattoon, Corning, N. Y., assignor to Corning Glass Works, Corning, N. Y., a corporation of New York

Application December 16, 1947, Serial No. 792,079

3 Claims. (Cl. 16—110)

1

The present invention relates to handles and is particularly concerned with improvements in facilities enabling firm, reliable and safe attachment of glass handles to kitchen utensils and the like. Glass handles have been successfully employed in combination with medium sized glass utensils wherein only moderate stresses are encountered in lifting such utensils when filled.

The object of the present invention is a glass handle assembly particularly suitable for use with a metal utensil.

In the accompanying drawing the invention has been illustrated, by way of example, as applied to a cast metal sauce pan. It is equally applicable to other types of metal utensils in which the handle socket may be formed as an integral part of the utensil or may constitute a separate element rigidly attached to the utensil by welding, riveting, clamping, or similar means.

Fig. 1 is a plan view partly in section showing a fragment of a sauce pan with a glass handle attached thereto in a manner in accordance with the invention.

Fig. 2 is a sectional elevation taken on line 2—2 of Fig. 1.

Fig. 3 is an exploded perspective view of the bolt and cushioning sleeve of the assembly.

The handle employed has the usual hand-grip portion 11 enlarged near the vessel end to form a shoulder 12 for abutment against the edges of walls 13—16 forming a handle socket 10 of a cross-sectional configuration and size to just easily receive the end 17 of the handle. Passing transversely through socket walls 13 and 14 are aligned apertures for receipt of a bolt 18 having an eccentric portion 20 which passes through a sleeve 21 occupying suitably provided grooves or notches 22 and 23 in the bottom of handle portion 17 and in the upper surface of socket wall 16 respectively. By turning the bolt 18 in a counter clockwise direction the eccentric portion 20 is moved toward the vessel, drawing the handle inward until the shoulder 12 thereof tightly engages the edges of walls 13—16. A lock nut 25 is then threaded onto bolt 18 tightly against the socket wall 13 to hold the bolt in its handle tightening position.

The handle 11, when made of glass, must be protected against abrasion and point loading. The sleeve 21, preferably composed of soft metal such as copper or the like, affords this protection since it readily conforms to irregularities in the glass surface engaged by it and serves as a bushing in which the eccentric portion 20 of bolt 18 can turn, thereby preventing abrasion between

2

the bolt and glass in the handle tightening operation. When the vessel assembly is subjected to heat, expansion of the parts occurs thereby increasing the pressure between the bolt and the glass. At such time the sleeve functions as a cushion to prevent destructive point loading. Obviously, if the handle material is composed of non-brittle material such as wood or metal, use of the sleeve 21 may be dispensed with.

Although applicant has disclosed but one method and/or means for causing the bolt 18 to bear against the glass in a direction to hold it tightly in its socket, other facilities for doing this will occur to those skilled in the art and are believed to be within the bounds of applicant's invention as claimed.

What is claimed is:

1. In a glass handle and metal vessel assembly, a socket latterly projecting from the vessel with its free end having an opening therein for receipt of a handle, said socket having apertures passing transversely therethrough, a handle having a portion occupying said socket and having a groove therein in alignment with said apertures and having a shoulder portion for abutment against that portion of the socket bordering its opening, means comprising a bolt having an intermediate circular portion occupying said groove and having circular end portions eccentric with respect to said intermediate circular portion, and occupying said apertures so that the bolt can be turned to bring said intermediate circular portion to bear against the surfaces of said groove opposite the shoulder portion to tightly draw the latter portion against that portion of the socket bordering its opening, and means for holding said bolt in the position to which it has been turned.

2. A structure such as defined by claim 1 wherein a cushion is arranged between the bolt and a wall of said groove.

3. A glass handle having a portion adapted to occupy a metal utensil handle socket opening, said portion having a groove therein adapted for alignment with apertures through the socket and having a shoulder for abutment against a handle-bordering portion of the socket, a bolt having an intermediate circular portion occupying said groove and having circular end portions eccentric with respect to said intermediate portion adapted to occupy the socket apertures so that it can be turned to bring said intermediate circular portion to bear against the surfaces of said groove opposite the shoulder to tightly draw the latter against the handle-bordering portion

of the socket, and means for holding said bolt in its turned position.
